UNITED STATES PATENT OFFICE

JOSEPH DANIELS, OF ESSEN-RUHR, GERMANY, ASSIGNOR, BY MESNE ASSIGNMENTS, TO THE KOPPERS COMPANY, OF PITTSBURGH, PENNSYLVANIA, A CORPORATION OF DELAWARE

TUNNEL OVEN

Application filed March 8, 1930, Serial No. 434,294, and in Germany March 9, 1929.

In connection with tunnel ovens, e. g. ovens used for firing refractory bricks, regenerators for preheating gas and air have been used in order to assist in maintaining a high and even 5 or regularly distributed temperature in the firing zone, the regenerator extending across or over the oven chamber.

According to my invention the uniformity of heating is increased by arranging numerous gas and air inlets, alternating with each other, side by side along the oven, in the firing zone, so that a practically continuous sheet of flame is obtained.

For this purpose I adopt the known practice of placing the regenerators in couples side by side, so that all the chambers along the firing zone are accessible from the front for cleaning purposes and repair of the checker work.

20 I may have a series of regenerators of normal width individual, communicating at the top with distributing ducts extending lengthwise of the oven, and connect the distributing ducts to discharge ducts leading to the oven chamber, arranged so that each pair of regenerators, heating gas and air respectively, feeds numerous ducts opening into the oven chamber, the gas inlets alternating with the air inlets.

25 In another modification I use a series of particularly narrow gas and air heating regenerators. With this arrangement I may dispense altogether with a distributing system in the hot, upper part of the oven, or 30 may reduce the same to ducts arranged in pairs, two from each regenerator leading to the oven chamber, and crossed so that the series of inlets into the oven chamber consists of gas inlets and air inlets alternating with each other. This method enables heating with rich gas to be effected in a very simple way, the rich gas being fed to the oven chamber from outside through the walls separating the regenerators.

40 45 Two examples of installations according to the invention are shown in the annexed drawings in Figs. 1 to 3 and Figs. 4 to 11 respectively.

Fig. 1 is a plan view,
50 Fig. 2 a cross-section, and

Fig. 3 a longitudinal section.

Fig. 4 is a cross-section taken in two different planes,

Figs. 5 and 6 being longitudinal sections, and

55 Figs. 7 and 8 horizontal sections in different planes,

Figs. 9, 10 and 11 are respectively a cross-section, a longitudinal section and a plan view showing to a larger scale the system of 60 ducts feeding gas and air from the regenerators to the oven chamber.

Referring first to Figs. 1 to 3, the firing zone of the tunnel oven 10 has a series of regenerative gas heaters 11 and regenerative 65 air heaters 12, alternating with each other. For each successive couple of these regenerators there is a forked supply duct 13, 14. The air and gas preheated in the checker work pass out into distributing ducts 15, 16, which 70 lie side by side, each pair of these ducts 15, 16 extending over one of the couples of regenerators 11, 12. Gas ducts 17, 17 and air ducts 18, 18 leading to the oven chamber alternate with each other and extend transversely of the ducts 15, 16, their outlets into the oven forming a continuous series of gas and air orifices alternating with each other. Dampers 19 are controlled from inspection 75 and service holes 20, for regulating the discharge from the several ducts 15 and 16 into the ducts 17 and 18 respectively.

The distributing ducts above the regenerators serve as equalizers for the distribution of gas and air along the sections of the 80 oven served by the respective regenerators, that is to say they correct irregularities in the streams of gas and air arising from irregularities in the checker-work. Additional regulation for obtaining the desired gradation of temperature is effected by means of the dampers. As these ducts in the upper part of the oven are very hot a substantial transfer of heat to the air and gas takes place 85 therein, so that the regenerators themselves need only be of moderate height.

In the modification shown in Figs. 4 to 11 the alternating regenerative gas heaters 11 and air heaters 12 discharge into ducts 18 leading from the tops thereof to outlets open- 90

ing into the oven chamber about midway between the top and bottom levels of that chamber. As shown in Figs. 4 to 7, the regenerators are served in groups of two or more 5 by means of supply ducts 25, but their supplies are separately regulatable by means of dampers 26. This arrangement of regulating dampers has the advantage of being in a cooler part of the oven, where the gas and 10 air are not yet pre-heated.

The distribution of air and gas to the regenerators depends on the gradation of temperature required in the oven. Dampers 20 are provided in the modification also, for ad- 15ditional regulation, so that "dead" corners in the checker work are largely avoided, where- as such corners are very liable to occur if the air or gas has to flow diagonally through the checker-work. The chambers and ducts be- 20low the regenerators serve as convenient dust collectors, which can easily be cleaned out by means of discharge ducts having shutters 35, these serving also as vents in case of explosion. The roof bricks of the distributing ducts, 25 which are also the floor bricks of the regenerators, can be taken out to give access to the distributing ducts from openings having shutters 27.

In order further to reduce the intervals be- 30tween the air and gas inlets into, the oven, without making the regenerators unduly narrow, there is provided, between the inlets served by each regenerator, an inlet 28 served by means of a branched duct 29, 30 (Figs. 9, 35 10, 11) from the next regenerator. Each of these feed ducts serves two inlets, one by means of the part 29 coming from the regenerator, and the other, namely the inlet 28, by means of the branch 30. Control of the 40 inlets 28 can be effected by means of the pas- sage 35. Instead of feeding the inlets 28 by means of branch ducts 30 at the lower ends of the ducts 29, the ducts 29 may have branches at the upper parts thereof, extend- 45ing round the ducts 18 and then passing vertically downwards.

Instead of feeding gas and air to the regenerators through the elbow unions 31 shown in Fig. 4, the same may be fed in di- 50rectly through the inlets, regulation of supply being effected at these inlets. The distributing ducts 25 then serve only for collecting the waste gases and leading them to an elbow union 31, the waste heat and regen- 55 erator temperature being regulated by means of floor dampers 26. This renders the regulation of inlet and discharge more independent.

For compound working with a supply of 60 rich gas the walls dividing the regenerators have flues 32 for this gas, with outlets 33 in recesses, as shown in Figs. 4 and 8. When changing over, an air damper 34 is opened, so that the graphite is burnt with fresh air 65 sucked in from outside, and the products of

combustion can pass directly to the adjacent air inlet.

In addition to the advantages already set forth the second modification described has the advantage that the masonry of the thin dividing walls is very fully utilized for regenerative heating, that is to say more fully than thick walls, which are only heated to a depth of a few centimeters during the usual half-hourly periods of heating up the regen- 75erators. The short distances between the walls make for strength of the structure, so that a tunnel wall thinner than usual can be used.

In coke-oven practice it has been proposed to divide up the regenerators more and more, that is to say to use narrow regenerators side by side instead of regenerators of the usual width, but of course the purpose in that case is not to secure a continuous sheet or strip of flame, but to provide a separate regenerator for each coke-oven chamber, the width of the regenerators depending ultimately on the width of the oven chambers and the thickness of their dividing walls. In that case the regenerator walls cannot by any means be as thin as with my invention, as they have to bear a heavy load including the charging applicances of the ovens, and in view of the considerable length of the oven chambers (say 90 10 meters or more) the regenerator roof must be strong enough for vehicles bringing the coal. These conditions do not arise with tunnel ovens, where the sub-division of the regenerators can be carried to any desired 95 length, and there is no need for vehicles on the roof.

What I claim is:

1. A tunnel oven with regenerators for preheating air and gas for combustion distributed along the firing zone, the said regenerators feeding air and gas to air and gas inlets alternating with each other along the tunnel in such a manner that a sheet or strip of flame is produced, regulatable as regards its local intensity.

2. A tunnel oven as claimed in claim 1, having distributing conduits extending lengthwise of the tunnels, communicating with the upper parts of the regenerators and with transversely disposed air and gas feed conduits leading to the alternately disposed air and gas inlets of the oven chamber.

3. A tunnel oven with regenerators for preheating air and gas for combustion distributed in pairs along the firing zone, the said regenerators feeding air and gas to the air and gas inlets alternating with each other along the tunnel firing zone in such manner that a sheet or strip of flame is produced, regulatable as to its local intensity, and in which each pair of consecutive air regenerators is fed by a common, central, forked air inlet.

4. A tunnel oven having a series of narrow gas heating and air heating regenerators dis- 123

tributed along the firing zone and arranged to feed to series of alternate gas and air inlets in the oven disposed sufficiently closely together to produce a practically uninterrupted strip of flame, without requiring a system of gas and air distributing ducts above the regenerators.

5. A tunnel oven as claimed in claim 4, wherein each regenerator has two discharge ducts leading to the oven chamber, crossed at their discharge ends so that the alternate air and gas inlets of the oven chamber are close together without the regenerators being excessively narrow.

10 6. A tunnel oven as claimed in claim 1, with flues in the dividing walls of the regenerators for introducing rich gas into the oven when such gas is used as an alternative for lean gas, or with lean gas alternatively.

20 7. A tunnel oven as claimed in claim 1 having below the regenerators distributing ducts whereby regenerators are connected in groups of two or more, said ducts being adapted for inlet and outlet of a gaseous medium alternately, or for outlet only.

25 8. A tunnel oven as claimed in claim 1, having below the regenerators distributing ducts whereby regenerators are connected in groups of two or more, said ducts being adapted for inlet and outlet of a gaseous medium alternately, or for outlet only, and dampers at the tops of the regenerators for controlling the flow therefrom to the inlets to the tunnel, and having dampers at the outlets of distributing ducts for separately regulating the feed to the regenerators of a group, whereby the flow through the regenerators may be kept even.

35 9. A tunnel oven as claimed in claim 1, with rich gas flues in the dividing walls of the regenerators for introducing rich fuel gas into the oven when such gas is used as an alternative for lean gas, or with lean gas, and in which an air inlet damper is provided for said flues and the outlets for the rich gas flues are in recesses in the wall of the oven chamber adjacent the regenerator air inlets, so that by opening the dampers for admitting air, when a change over to lean gas is made, graphite deposited in the rich gas flues can be 45 burnt and the products of combustion can pass directly to the adjacent air inlet without touching the over setting.

40 10. A tunnel oven with regenerators for preheating air and gas for combustion distributed in pairs along the firing zone, the said regenerators feeding air and gas to air and gas inlets alternating with each other along the tunnel in such manner that a sheet or strip of flame is produced, regulatable as 50 regards its local intensity.

45 11. A tunnel oven as claimed in claim 4, with flues in the dividing walls of the regenerators for introducing rich gas into the oven when such gas is used as an alternative for 55 lean gas, or with lean gas alternatively.

12. A tunnel oven as claimed in claim 10, with flues in the dividing walls of the regenerators for introducing rich gas into the oven when such gas is used as an alternative for lean gas, or with lean gas alternatively.

70 In witness whereof I affix my signature.

JOSEPH DANIELS.
